UNITED STATES PATENT OFFICE.

WILLIAM A. CUSHMAN, OF PROVIDENCE, RHODE ISLAND, ASSIGNOR TO
LA MOTHE MANUFACTURING COMPANY, OF NEW YORK, N. Y.

METALLIC CAR.

SPECIFICATION forming part of Letters Patent No. 236,786, dated January 18, 1881.

Application filed September 24, 1880. (No model.)

To all whom it may concern:

Be it known that I, WILLIAM A. CUSHMAN, of Providence, in the State of Rhode Island, have invented an Improvement in Metallic Cars, of which the following is a specification.

The floors of freight and passenger cars and the platforms of open cars have been made of iron tubes running lengthwise, with transverse tubes that are bound together by metallic bands. In cars of this kind transverse beams have been introduced, the same being of wood incased with metal, the longitudinal tubes passing through such transom-beams, and such beams being between the ranges of transverse tubes.

My present invention is for lessening the expense of construction, and for rendering the platform lighter and at the same time maintaining the durability of the structure.

In the drawings, Figure 1 is a side view of a portion of a railway-car platform. Fig. 2 is a partial plan of the same, and Fig. 3 is a partial cross-section at the line *x x*.

The longitudinal tubes *a a* and the tie-bands *b*, passing around the same, are similar to those shown in Letters Patent No. 185,446, except that only top and bottom tubes are used. By placing the longitudinal tubes together in pairs I am able to obtain great strength and lightness, and to introduce as many pairs of longitudinal tubes as are required for obtaining the necessary strength.

The length of the transverse beams *e* corresponds, or nearly so, to the width of the car, and each beam is of a width to fill the opening between the top and bottom tubes, and it is firmly clamped into place as the parts are driven together.

In some instances the transverse beam or timber *e* will be placed between the tubes *a*, and then the bands around the tubes will be driven up at each side of the beam to clamp the beam firmly between the tubes and bands. In this form the timbers may be notched on their edges to partially receive the tubes, as shown in the detached view, Fig. 4, or when the cross-beam is narrower than the distance between the longitudinal tubes, there may be metal shoes introduced, as at 3, Fig. 5, upon the edges of the timbers, so as to intervene between the tubes and the beam. The beams *e*

will usually each be made of a single piece of material; but I do not limit myself in this particular, as the same may be composed of two or three wooden strips driven together and bolted.

In laying the floor-plank the same rests directly upon the longitudinal metal tubes, and I find that the most convenient manner of securing the planks is to drive through the same long slender wrought-iron spikes, such spikes passing at one side of the tube, as shown in Fig. 5. Then I bend the spike partially around the tube and apply a semicircular grooved anvil below the tube, so as to receive the spike into the groove, and I finish driving the spike. During this operation the spike will be bent so as to firmly grasp the tube, and the point will re-enter the plank if the spike is long enough. If shorter spikes are used, the points may be received into the groove of the semicircular anvil and bent up thereby during the act of driving such spike.

If desired, the transverse beams may be faced with metal plates upon the vertical sides, as at *c*, in which case the top and bottom edges of these plates will be cut with segmental notches where the tubes cross the beams.

I am aware that in Letters Patent No. 170,480 there is a transverse beam of wood with tubes of iron passing through the same. In my improvement thereon the transverse beam is simply notched at the edges for the sides of the tubes to lie in such notches; hence the parts can be put together very rapidly, because the tubes do not have to be passed endwise through holes in the transverse beam.

I claim as my invention—

In the platform of a car, the longitudinal metal tubes, placed together in pairs, in combination with transverse beams of wood having notches at the edges and placed between the metal tubes, and metal bands around the tubes to clamp said tubes directly upon such beams, substantially as set forth.

Signed by me this 17th day of July, A. D. 1880.

WM. A. CUSHMAN.
